[57] CLAIM

The ornamental design for a data storage tape cartridge, as shown and described herein.

DESCRIPTION

FIG. 1 is a front isometric view of a data storage tape cartridge according to the present invention;

FIG. 2 is a top view of the cartridge shown in FIG. 1;

FIG. 3 is a side view of the cartridge shown in FIG. 1;

FIG. 4 is an opposite side view of the cartridge shown in FIG. 1;

FIG. 5 is a bottom view of the cartridge shown in FIG. 1;

FIG. 6 is a front view of the cartridge shown in FIG. 1; and,

FIG. 7 is a rear view of the cartridge shown in FIG. 1.

Those portions of the cartridge shown in broken lines are

included for illustrative purposes only and form no part of

the claimed design.
